SWING BRIDGE AND PROTECTIVE GATE
THEREFOR

Alfred Foshay, Aberdeen, Wash.

Application March 12, 1951, Serial No. 215,143

1 Claim. (Cl. 14—58)

1

This invention relates to a gate or guard wall construction for a bridge of the horizontally swinging draw type.

An important object of the present invention is to provide a gate construction as described wherein initial opening movement of the span will automatically cause the gate to rise instantaneously to blocking position, and to remain in said position as long as the span is open.

Another important object is to provide a construction as stated wherein movement of the span to closing position will gradually lower the gate, until said gate is fully lowered at the same time that the span moves to fully closed position.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawing

Fig. 1 is a top plan view of a gate and span construction in accordance with the present invention, portions being broken away.

Fig. 2 is a longitudinal section taken substantially on line 2—2 of Fig. 1.

Fig. 3 is an enlarged fragmentary detailed view of a gate mounted wheel.

Fig. 4 is a section taken substantially on line 4—4 of Fig. 3.

Fig. 5 is an enlarged section taken substantially on line 5—5 of Fig. 1, the dotted lines indicating the position of the gate when elevated, portions being broken away.

Fig. 6 is an enlarged fragmentary detailed perspective view of a hinged track section.

Fig. 7 is an enlarged detailed perspective view of another hinged section of the track.

Referring to the drawing in detail, a horizontally swinging draw span 1 has rotatable movement upon a column 2 formed upon the pier 3, said span having the arcuate end edges 4 and 5 that have correspondence with, and fit against, the arcuate end edges formed upon the approaches 6 and 7. When the span is in closed position, accordingly, an uninterrupted right of way is provided as seen in Fig. 1.

The present invention deals mainly with the provision of an automatic protective gate or guard wall for each approach, that will be automatically elevated when the span 1 is swung to opened

2

position, so as to prevent movement of traffic into the open space between the approaches.

Accordingly, secured to and depending from the bottom surfaces of the arcuate ends 4 and 5 of the span 1 are vertical supports 8, 9, and 10 for the arcuate trackways 11 at opposite ends of said span.

Each trackway 11, as readily seen from Figs. 6 and 7 is formed from suitable lengths of angle iron material, each of which is curved longitudinally so that the ends of said lengths, when butt-welded together, will form longitudinally curved trackways the curvature of which is in correspondence with and alignment with the end 15 4 or 5, as the case may be, of the draw span 1.

Each trackway, additionally, inclines downwardly from its opposite ends toward the center of the span, as best seen from Figs. 2 and 5, the center portion 12 of each trackway being disposed horizontally and being formed, close to the center line of the span, with a cut away portion 13 (Fig. 7) proportioned to be closed by a correspondingly shaped downwardly swinging door 14 connected by hinges 15 to the trackway and 25 having welded to its inner end the stop member 16 engageable when the door swings downwardly by a lug 17 welded to the center portion 12 of said trackway. When the door 14 swings upwardly, the stop member 16 engages against the 30 horizontal portion 12 of said trackway, so as to limit upward swinging movement of the door 14 beyond a position in which it is co-planar with the center portion 12 of said trackway.

Adjacent the outer end of said trackway 11, 35 there is formed in the trackway a cut away portion 18 proportioned to be closed (see Fig. 6) by the swinging door 19 connected by the hinge 20 to said trackway 11, upward swinging movement of said door 19 being limited by the stop lug 21 welded to the trackway 11. Formed on said trackway 11 is the upstanding bracket 22 in which is hooked one end of the spring 23, the other end of which is hooked to the door 19.

Bolted or otherwise secured to the bottom edge 45 of the gate 24 is a bearing 24 located at a central point between the opposite side edges of said gate, there being journaled in the bearing 24 the stub shaft 25 extended inwardly and having on its inner end the rotatably mounted wheel 26. Preferably, the mounting of the wheel 26 upon the stub shaft 25 is by means of a conventional roller bearing so as to assure rotation of the wheel upon the stub shaft with minimum friction.

55 The shaft 27, as readily seen from Figs. 3 and 4,

extends through a sliding block 27, which block 27 has its opposite side edges grooved so as to define flanges engageable slidably with the opposite side walls of the closed vertical groove formed in the depending slideway 28 secured to the center of the end edge of either approach.

As seen from Fig. 2, the gate 24' has up and down sliding movement in the slot 29 formed in and extended transversely across the approach 6 or 7 as the case may be, there being secured to the opposite ends of the gate 24' the cables 30 disposed within the upstanding hollow housings 31 formed with the vertical gate-receiving slots 32, said cables 30 being trained over the pulleys 33 and having secured to their opposite ends the counterweights 34.

Normally, the gate 24' is retained in the full line position illustrated in Fig. 5. However, assuming that the draw span 1 is swung laterally so as to open the space between the approaches, the initial movement of the draw span will cause the wheel 26, that is engaged rollably with the underside of the center portion 12 of the trackway, to be permitted upward movement, as soon as the trackway 11 moves laterally to the extent that the cut away portion 13 is positioned over said wheel. This occurs almost instantaneously with initial movement of the draw span 1.

As soon as this happens, the counterweights 34 are permitted to elevate the gates 24' immediately to the dotted line position illustrated in Fig. 5, so as to prevent the movement of traffic past said gates as long as the draw span is being opened or is in fully opened position.

As the gate 24' is elevated to its uppermost position, the block 27 will of course slide upwardly to the maximum extent within the closed slot of the slideway 28.

As the opening movement of the draw span continues, the outer end of the trackway 11 will engage the elevated wheel 26. However, the wheel 26 simply biases to open position the door 19, said open position of the door 19 being illustrated in dotted lines in Fig. 5 and being against the action of the spring 23 that normally tends to close said door.

Assuming now that it is desired to close the draw span, as the span moves to closing position, the initial portion of the trackway 11 that will engage the wheel 26 will be the under surface of the door 19. However, the door 19 will not at this time yield to the wheel 26, by reason of the presence of the stop lug 21.

Accordingly, as the span swings to closed position, the downwardly inclined portion of the trackway 11 will cam the wheel 26 downwardly, carrying with it the gate 24'. As the wheel 26 moves over the underside of the normally open door 14, said door will simply swing to its upper position in which it is in a plane with the remain-

ing portion of the center part 12 of said trackway.

Thus, when the span finally arrives at fully closed position, the gate 24' will be fully recessed so as to permit once again the passage of traffic over the span.

What is claimed is:

In a swingbridge of the type having spaced approaches and an elongated swing span mounted to move in a horizontal arcuate path from an active position in which the space between the approaches is closed by the span to an inactive position in which a clear passageway extends between the span and the approaches, each of said approaches having transversely extending recesses opening through their upper surfaces, gates mounted in each of said recesses for vertical movement from extended vertical active positions in which they extend upwardly across their respective approaches to inactive positions in which they lie below the top surfaces of the approaches, and means carried by the approaches and connected to the respective gates for moving the gates to upwardly extended active position across the approaches, means for moving the gates to and retaining them retracted in inactive position below the top surfaces of the approaches, said last named means comprising rollers carried by the gates below the approaches and movable therewith in vertical paths below the span, vertically extending transverse cam trackways carried by the span adjacent the ends thereof and extending into the paths of movement of the rollers for engaging the rollers and moving them, said trackways being inclined downwardly as they approach opposite ends of the span to cause the rollers to move downwardly and the gates to move downwardly into inactive position as the span moves to active position, each of said trackways having openings extending therethrough adjacent the lower ends thereof through which the rollers pass upon initial movement of the span toward its open inactive position relative to said approaches, means carried by the trackways for engagement by the rollers to close said openings immediately before the span moves to its fully open active position, said trackways having openings extending therethrough adjacent their ends through which the rollers pass when the span moves to its fully open inactive position, and yieldingly closed doors carried by the trackways adjacent said last named openings for closing said openings after the passage of the rollers therethrough.
